United States Patent Office

Des. 213,571
Patented Mar. 18, 1969

213,571

BATHROOM ACCESSORY CABINET OR SIMILAR ARTICLE

Peter M. Berend, Wooster, Ohio, assignor to Rubbermaid
Incorporated, Wooster, Ohio, a corporation of Ohio

Filed Sept. 5, 1967, Ser. No. 8,489

Term of patent 14 years

U.S. Cl. D33—16
Int. Cl. D6—01

FIG. 1

FIG. 2

FIG. 4

FIG. 1 is a plan view of a bathroom accessory cabinet or similar article embodying my new design.

FIG. 2 is a front elevation thereof.

FIG. 3 is an end elevation thereof.

FIG. 4 is a front perspective view of the cabinet. The rear surface of the cabinet is a flat planar surface. I claim:

The ornamental design for a bathroom accessory cabinet or similar article, as shown and described.
